UNITED STATES PATENT OFFICE.

BERNIE CHARLES KRIDLER AND JAMES C. BOYLE, OF FLINT, MICHIGAN, ASSIGNEES
TO THE SHINGLE LOCK COMPANY, OF FLINT, MICHIGAN, A CORPORATION OF MICH-
IGAN.

SHINGLE-LOCK-APPLYING MACHINE.

Application filed September 18, 1922. Serial No. 589,035.

To all whom it may concern:

Be it known that we, BERNIE CHARLES KRIDLER and JAMES C. BOYLE, citizens of the United States, and residents of Flint, 5 Genesee County, State of Michigan, have invented new and useful Improvements in Shingle-Lock-Applying Machines, of which the following is a specification.

Among the principal objects which the 10 present invention has in view are: to apply locks or fastening devices to shingles of certain classes with rapidity and ease; to secure the said locks upon flexible roofing shingles quickly and with ease; and to provide a machine for accomplishing the above 15 stated purposes which is simply and cheaply constructed.

Drawings.

20 Figure 1 is a side edge view of a machine of the character mentioned shown partly in section and in the loaded position preliminary to being actively disposed;

25 Figure 2 is a sectional view on enlarged scale of the machine, the section being taken as on the line 2—2 in Figure 5;

Figure 3 is a detailed view on enlarged scale showing the lock holding head of the 30 machine in closed position as at the completion of its operation;

Figure 4 is a detailed view on enlarged scale of one of the spring actuated trippers with which the machine is provided; and

35 Figure 5 is a top plan view of the machine shown in reduced scale and in operative position.

Description.

40 The shingle lock for attaching which to certain classes of shingles the present machine is designed is shown best in Figures 1 and 3 of the drawings. It is preferably constructed from sheet metal and has a body

45 portion 10 of desired height, generally equal to the thickness of a sheathing board or roofing strip used for supporting roofing shingles. From opposite edges of the body 10 are extended the wedges 11 and clips 12.

50 The said wedges and clips are extremities of overturned flanges of the body 10. One of the clips 12 is formed at the end of an elongated extension 13. The opposite clip 12 is

at the extremity of a shorter extension 14. The wedges 11 are designed to extend beneath the edges of adjacent sheathing strips of the roof construction while the clips 12 are pressed through and clinched upon the shingles indicated by the numeral 15.

The shingles 15 for which the locks above 60 described are particularly designed are constructed of semi-flexible material such as heavy roofing board or asbestos slabs. Shingles thus constructed are benefited by reinforcement disposed lengthwise thereof. 65 This is provided in the present instance by means of the extensions 13 and 14 which stiffen or strengthen the shingles while the clips 12 being clinched thereover hold the 70 structure rigid.

Certain of the locks 10 are shorter than others, and for this reason the heads 16 with which the press frame 17 is provided have two sets of supporting recesses indicated by the numerals 18 and 19 respectively. 75

When loading the heads 16 with locks to be attached to shingles the wedges 11 thereof are disposed in the recesses 18 and 19, the frame 17 being held in the upraised position shown in Figure 1 of the drawings, the un- 80

clinched clips 12 resting in juxtaposed relation to the stripper heads 20. The stripper heads 20, as best seen in Figure 4 of the drawings, are disposed at the end of plungers 85

21 held in the heads 16 and in bored recesses 22 provided therefor. Around each of the plungers 21 extends the spiral spring 23 with which each stripper is provided. The spring 23 normally advances the head 20 to the position shown in Figure 1 of the drawings, while the spring 23 compresses as shown in Figure 3 of the drawings to permit the head 16 to approach the shingle 15 sufficiently to overturn the ends of the clips 12 on the anvil 24.

90 The frame 17 consists of a series of reach bars spaced apart a distance equal to the width of the shingles to be provided with locks. There may be two or more of said reach bars in each frame. A hand bar 25 100 unites the various reach bars as also does the brace 26 which is extended across and secured to said reach bar near the hinged end thereof. As shown best in Figure 1 of the drawings the reach bars of the frame 17 105 have a series of hinge brackets 27 by which

the frame is pivotally mounted on a hinge rod 28 supported above the base board 29 by brackets 30.

The machine is peculiarly adapted for placing the locks on what may be termed imitation shingles, or shingle strips of various lengths such as shown in Figure 5 of the drawings, the exposed edges whereof are slotted to form spaces 31 imitating the partings between shingles of conventional form. When applying locks to shingles of this character the several locks 16 are loaded before the frame is depressed. In this condition the frame forces the various clips 12 upon the anvil 24 so that the curved end of the said anvil curls the said clips to the position shown in Figure 3 of the drawings. When pressure is removed from the hand bar 25 the springs 23 extend the stripper heads 20 to prevent the lift of the shingles 15. Prior to releasing the frame 17 it is moved slightly sidewise, the pressure being sufficiently relieved to avoid pulling the locks sidewise. This frees the various locks from the heads 16, the wedges 11 sliding easily from engagement with the recesses 18 and 19.

The anvils 24 are preferably made of metal of any suitable character, a groove 32 being routed therein. The ends of the said groove 32 are curved as best seen in Figure 3 of the drawings for curling the clips 12 when forced thereinto.

A gage strip 33 is held in position by wing nuts 34 so that the shingles 15 or shingle strips 15^a may be quickly adjusted on the base board 29.

It is obvious that this machine employed in the manner as above described enables the mechanic to quickly apply and with ease a large number of the locks to single piece shingles or strips of shingles laid on the base board 29 against the gage 33. It is also obvious that with shingles thus provided the construction is reinforced and the labor of laying or mounting the shingles on the roof is facilitated and quickened.

Claims.

1. A machine as characterized comprising a base board for supporting shingles; a reciprocating frame disposed above said board; a series of lock supporting heads mounted on said frame, said heads being each provided with engaging recesses for holding wedges on the locks being handled by said machine.

2. A machine as characterized comprising a base board for supporting shingles; a reciprocating frame disposed above said board; a series of lock supporting heads mounted on said frame, said heads being each provided with engaging recesses for holding wedges on the locks being handled by said machine; and a plurality of resilient strippers adapted for holding said shingles on said base board after said locks have been secured to said shingles.

3. A machine as characterized comprising a base board for supporting shingles; a reciprocating frame disposed above said board; a series of lock supporting heads mounted on said frame, said heads being each provided with engaging recesses for holding wedges on the locks being handled by said machine; and means pivotally mounting said frame on said base board, said means embodying a hinge rod and hinge brackets disposed thereon in sliding relation thereto.

4. A machine as characterized comprising a base board for supporting shingles; a reciprocating frame disposed above said board; a series of lock supporting heads mounted on said frame, said heads being each provided with engaging recesses for holding wedges on the locks being handled by said machine; a plurality of resilient strippers adapted for holding said shingles on said base board after said locks have been secured to said shingles; and a plurality of anvil members disposed in line with said heads for overturning the clip ends formed on said locks and for receiving the impact of said strippers.

5. A machine as characterized comprising a base board for supporting shingles; a reciprocating frame disposed above said board; a series of lock supporting heads mounted on said frame, said heads being each provided with engaging recesses for holding wedges on the locks being handled by said machine; a plurality of resilient strippers adapted for holding said shingles on said base board after said locks have been secured to said shingles; a plurality of anvil members disposed in line with said heads for overturning the clip ends formed on said locks and for receiving the impact of said strippers; and a plurality of gage members for determining the location of said shingles on said base board for receiving said locks.

BERNIE CHARLES KRIDLER.
JAMES C. BOYLE.
